UNITED STATES PATENT OFFICE.

MARTIN LÉONARD EDMOND DUVAL, OF PARIS, FRANCE, ASSIGNOR TO THE COMPAGNIE DE FIVES-LILLE, OF SAME PLACE.

AUTOMATIC REGULATOR FOR AIR-BRAKES.

SPECIFICATION forming part of Letters Patent No. 486,703, dated November 22, 1892.

Application filed February 18, 1892. Serial No. 422,028. (No model.)

To all whom it may concern:

Be it known that I, MARTIN LÉONARD EDMOND DUVAL, a resident of Paris, in the Republic of France, have invented a new and useful Improvement in Automatic Regulators for Air-Brakes, which improvement is fully set forth in the following specification.

Apparatus heretofore employed for stopping railway-cars act by means of air compressed by a pump on the locomotive or by a vacuum produced by a steam-ejector also carried by the locomotive. In both systems each vehicle is provided with a brake apparatus composed, essentially, of a cylinder having a piston acting upon a brake-rod and a distributing apparatus or triple valve, which is of different forms, according to the system of which it is a part, and the operation of which controls the air acting on the piston. All brake apparatus of the same train are fed by a general air-conduit, with which they are connected by branch pipes. One extremity of this conduit has a maneuvering-cock placed so that the engineer may operate it. The other extremity is simply closed by means of a stop-cock. When the engineer desires to apply the brakes, he opens the cock, allowing a certain quantity of air to escape from the main conduit. Consequently a reduction of pressure is produced in the latter throughout its length, and this reduction of pressure bringing into play the distributor allows the admission of air into the brake-cylinder from the auxiliary reservoir on each car. From this description it will be readily understood that if the main conduit is short the fall of pressure caused by operating the maneuvering-cock will be quickly transmitted and without sensible loss throughout the whole system and that the brakes will operate almost simultaneously; but this simultaneous action, deemed indispensable to secure the best results, is not realized to the same degree when the conduit is long, as is the case, for instance, in freight-trains, which consist often of from seventy to eighty vehicles. The fall of pressure is in such case greater at the forward than at the rear end of the train, causing irregularities in applying the brakes, and jerks and strains more or less violent in the train. What has been said regarding the

setting of the brakes applies, also, to the releasing of the same, which is effected by the re-establishment of pressure in the main conduit by putting it in communication with the air-reservoir of the pump.

The object of the present invention is to insure in the various conditions that occur the simultaneous action of the brakes without detriment to the promptness which is necessary, and the arrangement herein described permits this important result to be obtained. As a matter of example I have in the drawings accompanying this specification shown devices constructed in accordance with the invention.

Figure 1 is a vertical section. Fig. 2 is a plan view, partly in section, on line $x y z$ of Fig. 1. Fig. 3 is a detail view showing a modification; Fig. 4, a cross-section thereof; and Fig. 5 represents, partly by diagram, the position in which the regulator may be placed with reference to the other parts of the brake apparatus of the automatic type.

In appliances in use the communication between the distributor of each brake apparatus and the main conduit is effected by a pipe or orifice of uniform section, and for this reason the brakes nearest the engine come into action before those at a greater distance. This difficulty may be overcome or diminished by automatically retarding the action of the appliances nearest the engine by a partial closing of the orifice or pipe leading to the distributor or triple valve, and, on the other hand, advancing the action of those more remote by giving said orifices an initial section relatively large. On this principle is based the operation of the system herein explained, and which is designed to maintain the supply of air practically constant, whatever be the variation of pressure during the operation between the air of the distributor and that of the main conduit. The invention therefore consists in a device interposed between the main conduit and the distributor, which automatically adjusts the size of the orifice through which the air passes to and from the same in such manner that the size of the orifice or passage is diminished in inverse ratio to the degree of fluctuation of pressure. Thus in the brakes most remote

from the engine, where the change of pressure in setting or releasing the brakes is minimum, the size of the passage or orifice is the greatest, thus compensating for the diminution of the change of pressure. The passage or orifice is formed in part by a movable piece, whose position with respect to the fixed piece forming the other part of the orifice is regulated by an actuating device—such as a flexible diaphragm or piston—moved in one direction or the other by variations in pressure on the opposite sides thereof. This principle may obviously be embodied in many different forms of construction.

15 As shown in the drawings, the regulating apparatus comprises two chambers A and C, between which is a flexible but hermetic diaphragm J. The upper chamber A is in direct connection with the distributor by the passage B. The lower chamber C is in communication with the main conduit by orifice N. The two chambers, moreover, are in communication with each other through small channels D E F G H. Against the central rod I, to which is attached the diaphragm J, is pressed with constant pressure a small stationary valve K, whose lower edge or flange L is opposite to the greatest section of a groove m n when the brakes are released, thus forming the passage H. In the lower chamber C are two helical springs r s, which are compressed under the action of the diaphragm when the latter is depressed and react to restore it to its normal position. The small spring r alone is utilized in the normal operation of the brake. The auxiliary spring s is put in action only in case of rupture of the main conduit, as will be seen hereafter. During the normal running of the train the air-pressure is the same in the two chambers A and C, and in this condition the channel H presents to the flow of air its greatest section; but as soon as the engineer opens the regulating-cock the sudden fall of pressure produced in the main conduit, and consequently in the lower chamber C of the regulator, causes immediately the descent of the diaphragm of the central rod I, with which it is connected. This section of passage in the groove m n is diminished in proportion to the movement of the rod, becoming less as the reduction of pressure in the conduit increases. Since the reduction of pressure in the main conduit or train-pipe gradually decreases from the point at which the regulating-cock is situated, usually on the engine at the forward end of the train, it follows that the section or groove m n of the regulators should increase proportionately the greater the distance said distributors are situated from the regulating-cock, so that the regulator which is connected with the main conduit the greatest distance from the regulating-cock will present at H an opening which has the maximum section, and vice versa, allowing proportionate quantities of air to escape therethrough. Thus will be secured simul-

taneous action of all the brakes, it being of course understood that the form of the section of the groove and the elasticity of the springs are adjusted to suit the conditions of working. As soon as the equality of pressure tends to establish itself upon the two sides of the diaphragm J the spring r reacts in a very short time and brings the groove back to its normal position with respect to the valve K.

The explanation given above may be repeated with reference to the releasing of the brakes, only in this case the partial closing of the orifice takes place during the ascent of rod I, the same spring r being utilized for this operation. To complete this description we must examine the operation of the regulator when an accident causes the rupture of the main conduit, or the uncoupling of the flexible tubes which unite the ends of the conduit under the several cars. In such case, when the brakes work by compressed air the fall of pressure in the air-conduit is abrupt and excessive, and the spring r, whose flexibility should be great, may be insufficient to stand the pressure on the diaphragm. At this time spring s, which is stiffer than the first, comes into play, still further closing the orifice and tending to maintain the simultaneous action of the brakes, whatever may be the damage to the conduit.

The second spring s is not necessary with vacuum-brakes, the reduction of pressure in the main conduit being always less than one kilogram. The automatic regulator, of which Fig. 1 represents the general disposition, may assume various forms, according to the special application that is made thereof in each system of brakes. It may be isolated and connected with the main conduit or with the distributor by means of pipes, or may be combined with the distributor or triple valve in such a way as to form an integral part thereof. The flexible diaphragm may be made of any suitable substance and may be varied in form and dimensions. It may be a metallic diaphragm, constituting itself a spring. Finally, it is possible to dispense altogether with the small valve K by arranging the groove upon a rod of very small diameter adjusted to slide with slight friction but without lateral play in a cylindrical part of the casing. This construction is indicated in Fig. 3, in which the rod I, of small diameter, has the groove n adjacent to the lower end of the tubular piece K', which is screwed into the top of chamber A. In this case it will be more convenient to establish communication between chambers A and C by an exterior pipe, as P, than by a passage formed through the rod I.

Other modifications may also be made without departing from the spirit of the invention.

Having now fully described the said invention, what I claim, and desire to secure by Letters Patent, is—

1. An automatic regulator for air-brake systems, comprising two communicating cham-

bers, one being connected to the main conduit and the other to the distributer, a pressure-actuated device, such as a diaphragm, between the two chambers, and a rod carried thereby and having a groove of varying area in cross-section forming part of the passage to the distributer, so that a change of pressure in the main conduit causes a proportionate contraction of such passage, substantially as described.

2. The combination of the two communicating chambers, one connected with the distributer and the other with the main conduit, a flexible diaphragm between the two chambers, and a regulating device or rod carried by said diaphragm and having a groove or depression diminishing in sectional area from the middle toward the ends, a stationary piece opposite said groove or depression and cut away to form part of an orifice through which air passes to and from the distributer, substantially as and for the purpose set forth.

3. The combination of the two communicating chambers connected, respectively, with the distributer and with the main conduit, the regulating device or rod actuated by the difference of pressure between the two cham-

bers and having a groove or depression, whose sectional area diminishes toward the ends, a stationary piece forming with said groove or depression an orifice through which air passes to and from the distributer, and a spring tending to restore the rod to its normal position when equilibrium is established between the two chambers, substantially as described. 35

4. The combination, with the pressure-actuated regulator controlling the size of an orifice through which the air passes from the main conduit to the distributer, of a spring opposing the motion of said regulator when it moves responsive to a fall of pressure in the main conduit, and an auxiliary spring which co-operates with the first to resist the motion of said regulator in case of an abnormal reduction of pressure in the main conduit, substantially as described. 45

In testimony whereof I have signed this specification in the presence of two subscribing witnesses.
